UNITED STATES PATENT OFFICE

2,192,915

PUMP

Irving C. Jennings, South Norwalk, Conn.

Application September 4, 1936, Serial No. 99,469

26 Claims.

(Cl. 230—79)

This invention relates to hydroturbine pumps and compressors, and more particularly to improvements in the Nash Hytor compressor of the type shown in the United States patents to Jennings, Nos. 1,718,294, granted June 25, 1929, and 1,797,980, granted March 24, 1931.

The compressor or pump shown in these patents comprises an elliptical casing in which is arranged a circular rotor having a series of vanes defining peripheral displacement chambers. Liquid is placed in the pump casing, and the rotor is driven at high speed. The liquid in the casing will travel around with the rotor and by centrifugal action will follow the outline of the casing.

By this arrangement the liquid will be forced into and out of the displacement chambers as the rotor turns. Suitable ports are provided so that the piston action on the liquid thus obtained can be utilized either to exhaust or compress a fluid.

In some constructions considerable noise is produced in operation, caused by hydraulic shock in the machine. The water carried around by the rotor is forced into the displacement chamber of the rotor to compress the air or other fluid handled by the device, and when each individual blade or vane reaches the land of the pumping chamber, i. e., the point within the stator closest to the periphery of the rotor, the water or other pumping fluid is cut off with considerable shock, which causes a vibration resulting in noise, and strain on the blades, and necessitates an increase of horse power without doing useful work. Accordingly it is a primary object of the instant invention to minimize this hydraulic shock and eliminate noise, as well as to increase the efficiency of compressors and pumps of this general type.

Previously it was supposed that a close clearance was necessary between the rotor and the lands of the stator to prevent leakage of water. It has now been discovered, and shown by tests that actually a clearance at these points is beneficial.

Hence, another object of the invention contemplates the deliberate provision of clearance between the rotor and the narrowest part of the stator or casing.

The provision of this clearance results in largely eliminating the hydraulic shock, as a portion of the pumping liquid is thus permitted to escape ahead of the rotor. This means that the sharp cut-off of pumping liquid heretofore thought necessary, is eliminated, thereby reduc-

ing hydraulic shock, minimizing vibration and overcoming ancillary objections.

At the same time, the increase in the velocity of the pumping liquid into the next lobe, starts the liquid working in the next lobe of the compressor, with attendant increase in efficiency. The volume delivered by the compressor is slightly reduced by this clearance at the lands, but the required horse power is reduced considerably more, so that not only is the shock and noise greatly eliminated, but the actual efficiency of the machine is improved.

Other advantages attendant upon the provision of this clearance at the points specified, in addition to the elimination of shock and the increase in operating efficiency are the reduction in liability of the compressor towards jamming, as if foreign material gets into the pump it is much less likely to jam when the clearance is provided, and also, the manufacturer does not have to be held to as close limits as heretofore.

To the attainment of the foregoing and other objects which will appear as the description proceeds, reference may be made to the accompanying drawing, in which:

Figure 1 is a longitudinal sectional elevation of a compressor embodying the improvements; and

Figure 2 is a transverse sectional elevation taken along the line 2—2 of Figure 1.

Referring more particularly to the drawing in which like reference numerals designate like parts, there is provided a casing or stator 10 having a pumping chamber of elliptical shape to provide lobes 11 and 12 separated by lands 13 and 14. Extending through the stator is a shaft 15 upon which is mounted the rotor 16, of generally cylindrical shape. This rotor, as is usual in Nash pumps, is divided by substantially radial vanes 17 into a series of rotor pockets or buckets 18, each of which forms a displacement chamber 40 having a port or opening 19 in the bottom thereof to establish communication with the inlet ports 20 and 21 formed in the stator hub 22. This hub, of course, includes suitable inlet passages 23 and outlet passages 24 communicating with the inlet and outlet ports.

A separator member 25 may be provided intermediate the ends of the rotor for the dual purpose of strengthening the vanes 17 and reducing cross currents, or surging within the displacement chambers. The inner wall of the pumping chamber may be provided with a similar separating member, opposite the baffle or member 25 as disclosed in Patent No. 1,797,980.

The length of the vanes 17 is such that the 55

diameter of the rotor is less than the shortest internal diameter of the pumping chamber, in order to provide a real clearance space indicated at 26 between the rotor and the lands 13 and 14.

5 This clearance is of course greater than the usual machined running clearance heretofore thought necessary to prevent leakage of pumping fluid at the lands.

10 The amount of clearance provided, that is, the side of the clearance space between the rotor and the stator at the lands will of course vary with different compressors, but as one example which is illustrative of the fact that it is possible to run with a real clearance, it has been found that 15 with a rotor of about twelve inches in diameter a clearance of approximately $\frac{1}{8}$ of an inch at a lobe can be used to advantage. This of course is a real clearance as contrasted with a "machine fit" or running clearance as now generally used. 20 The foregoing example is intended as but illustrative and not as limiting. Experience has shown that a range of clearance giving beneficial results varies from slightly above to slightly below the given example, i. e., from approximately 25 three-fourths percent to two and one-fourth percent, or when, as in the given illustrations there are two diametrically opposed lands, the spacing of the rotor from the interior of the stator will range a total distance of from approximately one and one-half percent to 30 approximately four and one-half percent of the diameter.

As stated heretofore, the amount of clearance varies with different compressors; in fact, the 35 clearance or, for that matter, the total spacing of the rotor will vary with higher differentials at high speed, which is to be expected because of the fact that more of a squeeze will take place. In any event, it will be obvious that there will 40 be a proportioned relation between the amount of clearance, or the total spacing of the rotor on a diameter taken through the lands, and the rotor diameter. The ranges referred to herein, when given in terms of total distance will, as 45 stated above, vary from approximately one and one-half to four and one-half percent, or when given in terms of clearance, i. e., between a land and the rotor periphery, will be just half, or from three-fourths to two and one-fourth 50 cent of the rotor diameter.

The separating member 25 and the shrouds 27 may be extended beyond the vanes 17 if desired, to maintain a running fit with the stator, but this will in no wise affect the clearance between the 55 outer edges of the vanes 17 and the interior of the casing.

In the operation of pumps provided with a clearance as above described it has been found that hydraulic shock, vibration, noise, and blade 60 strain have been largely eliminated, and that while there will be some reduction in volume there is a greater reduction in horse power required, which means a net gain in efficiency, and further the liability of jamming when foreign 65 material gets into the pump is greatly reduced.

Obviously, manufacturing costs are reduced in that the manufacturer does not have to be held to as close limits as heretofore.

While the liquid used in the pumping action 70 is designated "water" in the specification, it will be understood that this designation is illustrative only, as other liquids may be substituted without impairing the utility or advantages of the invention or necessitating any mechanical alteration therein.

Having thus fully described my invention, what I claim as new and desire to secure by Letters Patent is:

1. In a hydro-turbine pump of the type using liquid as a pumping medium, the combination of a substantially circular rotor with an elliptical casing providing lobes therefor, said rotor having vanes providing displacement chambers about the periphery of the rotor, the periphery of the vaned portion of the rotor being spaced on a 10 diameter through the lands of said casing a total distance approximating from one and one-half percent to four and one-half percent of the rotor diameter, whereby to pass pumping liquid freely from one lobe to the next adjacent lobe, thereby 15 to increase the velocity of the pumping liquid in said adjacent lobe and reduce hydraulic shock.

2. In a hydro-turbine pump of the type using liquid as a pumping medium, the combination of a substantially circular rotor with an elliptical casing providing lobes therefor, said rotor having vanes providing displacement chambers about the periphery of the rotor, the periphery of the vaned portion of the rotor being spaced from the lands to provide clearances between the rotor and the 20 lands approximating from three-fourths percent to two and one-fourth percent of the rotor diameter, whereby to insure escape and free passage of the pumping liquid ahead of the vaned portion of the rotor from one lobe to the next, to reduce 25 hydraulic shock and increase operating efficiency.

3. In a hydro-turbine pump of the type using liquid as a pumping medium, the combination of a substantially circular rotor provided with peripheral displacement chambers, with a pump casing therefor having pumping lobes and a land, the greatest diameter of said rotor through said chambers being less than the cross sectional diameter of said casing through said land, to provide clearances between the periphery of the 35 vaned portion of said rotor and the land approximating from three-fourths percent to two and one-fourth percent of the rotor diameter, whereby pumping liquid will pass freely from one lobe to the next adjacent lobe to increase the 40 velocity of the liquid in said adjacent lobe and reduce hydraulic shock.

4. In a hydro-turbine pump of the type using liquid as a pumping medium, the combination of a substantially circular rotor provided with peripheral displacement chambers, with a pump casing therefor having pumping lobes separated by lands, the greatest diameter of said rotor through said chambers being less than the cross sectional diameter of the casing 50 through said lands, the periphery of the vaned portion of said rotor being spaced on a diameter through the lands of said casing a total distance approximating from one and one-half percent to four and one-half percent of the rotor diameter. 55

5. In a hydro-turbine pump of the type using liquid as a pumping medium, the combination of a substantially circular rotor provided with peripheral displacement chambers, with a pump casing therefor having a plurality of successively 60 operative pumping lobes separated by lands, and means to start the pumping liquid to work in one lobe prior to completion of its work in the preceding lobe, including clearances between the rotor and the lands approximating from three-fourths percent to two and one-fourth percent 65 of the rotor diameter.

6. In a hydro-turbine pump of the type using liquid as a pumping medium, the combination of a substantially circular rotor provided with pe- 70 75

5 peripheral displacement chambers, with a pump casing therefor having a plurality of successively operative pumping lobes separated by lands, and means to eliminate hydraulic shock including a spaced relation of the periphery of the rotor through said displacement chambers to the lands on a diameter through the lands, a total distance greater than required for free running clearance, wherein said total distance approximates from 10 one and one-half percent to four and one-half percent of the rotor diameter.

7. In a hydro-turbine pump of the type using liquid as a pumping medium, the combination of a substantially circular rotor provided with peripheral displacement chambers, with a pump casing therefor having a plurality of successively operative pumping lobes separated by lands, and means for starting the pumping liquid to work in one lobe prior to completion of its work in the preceding lobe, including a spaced relation of the periphery of the rotor through said displacement chambers to the lands on a diameter through the lands, a total distance greater than required for the free running clearance, said total distance approximating from one and one-half percent to four and one-half percent of the rotor diameter.

8. In a hydro-turbine pump of the type using liquid as a pumping medium, the combination of a substantially circular rotor provided with peripheral displacement chambers, with a pump casing therefor having a plurality of successively operative pumping lobes separated by lands, said rotor being spaced about its periphery through said displacement chambers from said lands of the casing on a diameter through the lands, a total distance approximating from one and one-half percent to four and one-half percent of the rotor diameter, whereby to release a portion of the pumping liquid in one lobe and to start said released portion of liquid to work in a successive lobe, prior to completion of the pumping action in the first lobe, thus minimizing hydraulic shock at the lands.

9. In a hydro-turbine pump of the type using liquid as a pumping medium, the combination with a rotor provided with peripheral displacement chambers, and a pump casing therefor, having a plurality of successively operative pumping lobes separated by lands, of means to increase the velocity of pumping liquid from one lobe into a successive lobe and to reduce hydraulic shock and minimize vibration including a proportioned relation of the rotor diameters with respect to the internal diameter of the casing through said displacement chambers from land to land such as to space the periphery of the rotor from said lands on a diameter through the lands, a total distance approximating from one and one-half percent to four and one-half percent of the rotor diameter to provide clearances, effective to release a portion of the pumping liquid in one lobe and to start said released portion of liquid to work in a successive lobe prior to completion of the pumping action in the first lobe.

10. In a hydro-turbine pump of the type using liquid as a pumping medium, the combination of a rotor and a stator providing a lobe casing therefor, the greatest diameter of the operating portion of said rotor being appreciably less than the smallest internal diameter of said casing, and the periphery of said operating portion being spaced at each of the lands of said casing a distance approximating from three-fourths percent to two and one-fourth percent of the rotor diameter, whereby to pass pumping liquid freely from

one lobe into the next adjacent lobe, during the pumping action, thereby to increase the velocity of the pumping liquid in said adjacent lobe, and reduce hydraulic shock.

11. In a hydro-turbine pump of the type using liquid as a pumping medium, the combination of a rotor and a stator providing a lobe casing therefor, and means providing a clearance between the operating portion of said rotor and casing at the smallest internal diameter of said casing, sufficiently great to pass pumping liquid freely from one lobe into the next adjacent lobe, during the pumping action, thereby to increase the velocity of the pumping liquid in said adjacent lobe, and reduce hydraulic shock, said clearance approximating from three-fourths percent to two and one-fourth percent of the rotor diameter.

12. In a hydro-turbine pump of the type using liquid as a pumping medium, the combination of a rotor and a stator providing a lobe casing therefor, the greatest diameter of the operating portion of said rotor being appreciably less than the smallest internal diameter of said casing, and the periphery of said operating portion being spaced at each of the lands of said casing a distance approximating from three-fourths percent to two and one-fourth percent of the rotor diameter, whereby to pass pumping liquid freely from one lobe into the next adjacent lobe, during the pumping action, thereby to increase the velocity of the pumping liquid in said adjacent lobe, and reduce hydraulic shock, and means at the periphery of the rotor effective to maintain a close running fit between the rotor and stator.

13. In a hydro-turbine pump of the type using liquid as a pumping medium, the combination of a rotor and a stator providing a lobe casing therefor, and means providing a clearance between the operating portion of said rotor and casing at the smallest internal diameter of said casing, sufficiently great to pass pumping liquid freely from one lobe into the next adjacent lobe, during the pumping action, thereby to increase the velocity of the pumping liquid in said adjacent lobe, and reduce hydraulic shock, said clearance approximating from three-fourths percent to two and one-fourth percent of the rotor diameter, and means at the periphery of the rotor effective to maintain a close running fit between the rotor and stator.

14. In a hydro-turbine pump of the type using liquid as a pumping medium, the combination of a substantially circular rotor with an elliptical casing providing lobes therefor, said rotor having vanes providing displacement chambers about the periphery of the rotor, said rotor also having shrouds defining side walls for said chambers, the greatest cross sectional diameter of said rotor through said vanes being appreciably less than the smallest internal diameter of said casing, the periphery of the vaned portion of said rotor being spaced at the lands of said casing a distance effective to pass pumping liquid freely from one lobe into the next adjacent lobe, during the pumping action, thereby to increase the velocity of the pumping liquid in said adjacent lobe, and reduce hydraulic shock, and the cross sectional diameter of said rotor through said shrouds being greater than the diameter through the vanes.

15. In a hydro-turbine pump of the type using liquid as a pumping medium, the combination of a substantially circular rotor provided with peripheral displacement chambers, said rotor also having shrouds defining side walls for said chambers, with a pump casing therefor having a

- pumping lobe and a land, the greatest diameter of said rotor through said chambers being less than the cross sectional diameter of said casing through said land, and the periphery of the chambered portion of said rotor being spaced from said land a distance effective to pass pumping liquid freely from one lobe into the next adjacent lobe, during the pumping action, thereby to increase the velocity of the pumping liquid in said adjacent lobe, and reduce hydraulic shock, and the cross sectional diameter of said rotor through said shrouds being greater than the diameter through the vanes.
16. In a hydro-turbine pump of the type using liquid as a pumping medium, the combination of a substantially circular rotor provided with peripheral displacement chambers, said rotor also having shrouds defining side walls for said chambers, with a pump casing therefor having a plurality of successively operative pumping lobes separated by lands, and means to start the pumping liquid to work in one lobe prior to completion of its work in the preceding lobe, including a clearance between the operative portion of the rotor and the lands effective to pass the pumping liquid freely from lobe to lobe during pumping action, thereby increasing the velocity of the pumping liquid as it enters a lobe, and the cross sectional diameter of said rotor through said shrouds being greater than the diameter through the vanes.
17. In a hydro-turbine pump of the type using liquid as a pumping medium, the combination of a substantially circular rotor provided with peripheral displacement chambers, said rotor also having shrouds defining side walls for said chambers, with a pump casing therefor having a plurality of successively operative pumping lobes separated by lands, and means to reduce hydraulic shock including a spaced relation of the periphery of the rotor through said displacement chambers to the lands a distance greater than required for free running clearance, whereby pumping liquid passes freely ahead of the displacement chambers, from one lobe into the next adjacent lobe, during the pumping action, and the cross sectional diameter of said rotor through said shrouds being greater than the diameter through the vanes.
18. In a hydro-turbine pump using liquid as the pumping medium the combination of a rotor having a portion operating in the pumping medium, with a lobe casing therefor, having lobes separated by lands, and means, including the operating portion of said rotor, to pass pumping liquid freely from one lobe into the next adjacent lobe during the pumping action, to increase the velocity of the pumping liquid in said adjacent lobe and to reduce hydraulic shock, said rotor being spaced from each of the lands a distance approximating from three-fourths percent to two and one-fourth percent of the rotor diameter.
19. In a hydro-turbine pump using liquid as the pumping medium, the combination of a rotor having a portion operating in the pumping medium, with a lobe casing therefor, having lobes separated by lands, and means including the operating portion of said rotor to increase the velocity of the pumping liquid above normal from one lobe to the next adjacent lobe, during pumping action, to start the liquid working in said adjacent lobe and to reduce hydraulic shock, said rotor being spaced from each of the lands a distance approximating from three-fourths percent to two and one-fourth percent of the rotor diameter.
20. In a hydro-turbine pump using liquid as the pumping medium, the combination of a rotor having a portion operating in the pumping medium, with a lobe casing therefor, said rotor having vanes providing displacement chambers about the periphery of the rotor, and shrouds defining side walls for said chambers, the greatest cross sectional diameter of said rotor through said vanes being appreciably less than the smallest internal diameter of said casing, and the diameter of the rotor through said shrouds being greater than that through the vanes, said shrouds and casing being proportioned to maintain a close running fit between the rotor shrouds and the casing.
21. In a hydro-turbine pump using liquid as the pumping medium, the combination of a rotor having a portion operating in the pumping medium, with a lobe casing therefor, said rotor having vanes providing displacement chambers about the periphery of the rotor, and shrouds defining side walls for said chambers, the diameter of the rotor through said vanes being less than the diameter of the rotor through said shrouds, and means providing a close running fit between said shrouds and the interior of the casing.
22. In a hydro turbine pump using liquid as a pumping medium, the combination of a pumping chamber having a lobe and a land, with a rotor having a portion operating in the pumping medium, said rotor having vanes providing displacement chambers about the periphery of the rotor, and shrouds defining side walls for said chamber, and means providing a clearance between the periphery of the rotor at the vanes and the interior of the pumping chamber at said land, approximating from one and one-half percent to four and one-half percent the diameter of the rotor.
23. In a hydro turbine pump using liquid as a pumping medium, the combination of a pumping chamber having a lobe and a land, with a rotor having a portion operating in the pumping medium, said rotor having vanes providing displacement chambers about the periphery of the rotor, and shrouds defining side walls for said chamber, means providing a clearance between the periphery of the rotor at the vanes and the interior of the pumping chamber at said land approximating from one and one-half percent to four and one-half percent the diameter of the rotor, and means providing a close running fit between the rotor and the interior of the chamber adjacent the periphery of the shrouds.
24. In a hydro turbine pump using liquid as a pumping medium, the combination of a pumping chamber having a lobe and a land, with a rotor having a portion operating in the pumping medium, said rotor having vanes providing displacement chambers about the periphery of the rotor, means providing a clearance between the periphery of the rotor at the vanes and the interior of the pumping chamber at said land approximating from one and one-half percent to four and one-half percent the diameter of the rotor, and means providing a close running fit between the peripheral edges of the rotor and the interior of the chamber, adjacent the land.
25. In a hydro turbine pump using liquid as a pumping medium, the combination of a pump casting for said pumping medium and provided with a lobe and a land, of a rotor having a portion op-

erating in the pumping medium, said rotor having vanes providing displacement chambers about the periphery of the rotor, and shrouds defining side walls for said chambers, the cross sectional diameter of the rotor through the vanes being appreciably less than the cross sectional diameter of the casing through that portion of the land adjacent the vanes, and the cross sectional diameter of the casing at points adjacent the land and the shrouds being substantially that of the cross sectional diameter through the rotor at the shrouds, said rotor and casing being proportioned to maintain a close running fit between said shrouds and the casing.

15 26. In a hydro turbine pump using liquid as a

pumping medium, the combination of a pump casing for said pumping medium and provided with a lobe and a land, of a rotor having a portion operating in the pumping medium, said rotor having vanes providing displacement chambers about the periphery of the rotor, and shrouds defining side walls for said chambers, means providing a clearance between the vanes and that portion of the land which co-operates therewith greater than the clearance between the shrouds and that portion of the land which co-operates with the shrouds, and means providing a close running fit between the shrouds and its co-operating portion of the land.

IRVING C. JENNINGS. 15
